United States Patent

Des. 239,653

Patented Apr. 20, 1976

239,653

RADIO

Donald J. Booty, Frankfort, Ill., assignor to
Amico, Inc., Philadelphia, Pa.

Filed Apr. 17, 1974, Ser. No. 461,678

Term of patent 14 years

Int. Cl. D14—03

U.S. Cl. D56—4 B

FIG. 1

FIG. 2

FIG. 3

FIG. 4

FIG. 5

FIG. 1 is a front elevational view of a radio showing my new design;

FIG. 2 is a right side elevational view, the left side being a mirror image thereof;

FIG. 3 is a rear elevational view;

FIG. 4 is a top plan view; and

FIG. 5 is a bottom plan view.

I claim:

The ornamental design for a radio, substantially as shown and described.
